CONTAINER

Gustaf Örström, Alsten, Sweden, assignor to
 Aktiebolaget Gerh. Arehns Mekaniska Verkstad,
 Stockholm, Sweden, a joint-stock company of
 Sweden

Application February 19, 1937, Serial No. 126,715
 In Sweden February 21, 1936

3 Claims. (Cl. 229—14)

This invention relates to improved containers, and more particularly bags or cartons having double walls one of which constitutes a relatively thin lining or cover.

5 It is a main object of my invention to provide a container of the type referred to having a very flat and tightly coiled top closure and nevertheless a thick, resistant and tight body portion.

In the drawing:

10 Fig. 1 is a perspective view of an embodiment of a carton having a lining;

Fig. 2 is a perspective view of the partly closed carton; and

15 Fig. 3 is a longitudinal sectional view of the sealed carton.

Referring to the drawing, the carton or envelope 8 of stiff material encloses a thin lining 11 of flexible material, and the upper end of the carton has two cut out and oppositely disposed triangular flaps 9 and two cut out and oppositely disposed rectangular flaps 10 and 13. As shown in Fig. 2, the four flaps serve to fold the lining 11 when the package is to be sealed by closing the outwardly projecting top end of the lining. When the flaps 9, 10 and 13 together with part 25 of the lining are folded down upon the contents of the package the lining is folded transversely about the front edge 14 of the flap 13, and the outwardly projecting end 12 (Fig. 2) of the lining is folded reversely about the front edge 15 of the flap 10 and folded to superimpose the flap 10 and form a flat and very tight closure which not only seals the inner lining but also the interspace between the inner lining and outer envelope.

35 The coiled fold 5 obtained is covered with a sealing band 6 the ends of which are pasted to the sides of the carton. Thereby, the closure coil will not be injured when it is opened, but the package is well adapted for the storage of its contents until it is completely emptied.

I claim:

1. A container comprising a carton having a lining, said carton having at its upper edge two oppositely disposed, cut out, triangular, inwardly

bent closure flaps that cover said lining and two oppositely disposed, cut out, rectangular flaps that are bent down upon said triangular flaps so that part of said lining is clamped directly between said rectangular and triangular flaps, said rectangular flaps overlapping one another in part, said lining projecting beyond said flaps and being bent rearwards about the front edge of the uppermost of said rectangular flaps to form a top closure covering said front edge.

2. A container having a stiff envelope and a lining, said envelope having at its upper edge a lower pair of oppositely disposed cut out inwardly bent closure flaps and an upper pair of oppositely disposed closure flaps which are bent inwardly over both the lower flaps, the top end of said lining projecting beyond said flaps and being folded transversely in opposite directions and covering the front marginal portions of both of said upper flaps to secure said upper flaps in folded down position and to seal the space between the lining and envelope, part of said lining superimposing said lower flaps and being superimposed by said upper flaps, and means for holding said projecting portion of the lining in folded down position.

3. A container having a stiff envelope and a lining, said envelope having at its upper edge a lower pair of oppositely disposed cut out inwardly bent closure flaps and an upper pair of oppositely disposed closure flaps which are bent inwardly over both the lower flaps, the top end portion of said lining projecting beyond said flaps and being folded transversely in opposite directions and covering the front marginal portions of both of said upper flaps to secure the upper flaps in folded down position and to seal the space between the lining and envelope, part of said lining superimposing said lower flaps and said part being superimposed by said upper flaps, and a sealing strip superimposing the top end portion of said lining when folded and being attached to opposite sides of said envelope.

GUSTAF ÖRSTRÖM.
